SKATE BOARD

Thomas E. Schell, 2460 Delisle Court,
Glendale, Calif. 91208

Filed July 27, 1970, Ser. No. 24,136

Term of patent 14 years

Int. Cl. D21—01

U.S. Cl. D34—15

FIG. 1 is a perspective view of the skate board showing my new design;

FIG. 2 is a bottom plan view thereof;

FIG. 3 is a side elevational view thereof;

FIG. 4 is a front elevational view thereof; and

FIG. 5 is a top plan view thereof.

I claim:

The ornamental design for a skate board, as shown.
